United States Patent Office

Des. 203,735
Patented Feb. 8, 1966

203,735

COMB HOLDER

Menno Bellar, 21 Rockland St., Fitchburg, Mass.

Filed Apr. 24, 1964, Ser. No. 79,691

Term of patent 3½ years

(C. D86—10)

FIG. 1

FIG. 2

FIG. 1 is a view in front elevation of a comb holder showing my new design, and

FIG. 2 is an edge view thereof, looking in the direction of arrow 2 in FIG. 1. The reverse side is plain.

I claim:

The ornamental design for a comb holder, as shown and described.
